UNITED STATES PATENT OFFICE.

JEAN B. DAUDELIN, OF FALL RIVER, MASSACHUSETTS.

LOOM SHUTTLE.

1,413,103.

Specification of Letters Patent. Patented Apr. 18, 1922.

Application filed February 2, 1920, Serial No. 355,674. Renewed May 31, 1921. Serial No. 473,775.

To all whom it may concern:

Be it known that I, JEAN B. DAUDELIN, a citizen of the United States, residing at Fall River, county of Bristol, Commonwealth of Massachusetts, have invented certain new and useful Improvements in Loom Shuttles, of which the following is a specification.

This invention relates to threading eyes for loom shuttles, and particularly to an eye or bushing of porcelain or other hard non-groovable material. Such eyes are especially adapted for use with a hard-drawn filling such as silk thread, the tendency of which is to cut the usual wire or metallic eye. Although the advantages of a bushing of this character are apparent, one factor which has prevented their general use has been the difficulty of properly fastening the bushing in the threading eye of the shuttle. Where glue alone is relied upon, the bushing has been liable to drop out by reason of the glue loosening during the run of the shuttle. The varying conditions of temperature and humidity in the different working rooms of the mills also contribute towards this result.

To the end therefore of providing a bushing which will be positively retained in the threading eye under all conditions of use of the shuttle, and which will effectively direct the filling into the eye and prevent improper escape thereof during the run of the shuttle, I have devised my present invention, the construction and operation of which, together with a selective embodiment which well illustrates the principles involved, is disclosed in the following specification and the drawings forming a part thereof, throughout which like reference characters are correspondingly applied, and in the drawings:

Fig. I is a plan view of the threading end of a shuttle equipped with our invention.

Fig. II is a longitudinal section thereof on the line II-II, of Fig. III.

Fig. III is a side elevation.

Fig. IV is a transverse section on the line IV-IV of Fig. III, and

Fig. V is a detail view of the bushing removed.

I have indicated at 1 the shuttle body which is provided with the usual bobbin chamber 2, threading eye 3, and threading slots 4 and 5 connecting the bobbin chamber

with the eye. The slot 4 may be guarded, as indicated at G.

Arranged in the eye 3 is a bushing which is so designed as to be practically keyed in the shuttle and thus to be substantially permanently fixed therein. The bushing 6 is preferably made of some hard non-groovable material as porcelain or the like and consists of a simple tube having an axial bore 7 into which a longitudinal thread inlet 65 slot 8 opens along the upper face of the bushing. Integrally formed upon the relatively flat base portion 61 of the bushing is a pair of oppositely disposed longitudinally extending beads or keys 9 and 10 which 70 snugly fit in correspondingly shaped counter bores 31 of the eye 3 and thus fix the bushing within the shuttle eye. By this construction the cylindrical portion of the bushing above the keys 9 and 10 may fit relatively loosely 75 in the bore 3, the snug fit of the keys themselves being relied upon to fix the position of the bushing. If desired, the outer or delivery end of the bushing may be slightly undercut to leave a portion 11 overhanging 80 the bore 7 and serving as a barrier to prevent the filling from lifting out of the bore during the run of the shuttle.

At the delivery end of the threading slot 5 the wood of the shuttle adjacent the eye 85 3 is cut away as indicated at 12 to provide an upwardly curved passage which extends as a continuation of the slot 5 and leads the filling upwardly and under the eye guard 13, so that the filling is laid through the 90 slot 8 into the bore 7 of the bushing 6 from above in threading. The guard 13 is a simple staple-like member set across the delivery end of the bushing as best shown in Fig. III, with its pointed legs embedded in 95 the wood of the shuttle, and between said legs, bent to provide a relatively downwardly inclined portion 14 overlying the passage 12 adjacent its juncture with the end of the slot 4 and providing a barrier 100 past which the filling twists as it is carried upwardly by the curved adjacent wall of the bushing towards the thread inlet slot 8. The guard 13 as a whole assists to prevent improper escape of the thread from the bore 105 7 of the bushing 6, as by a direct upward lifting movement, after the shuttle has been threaded.

In assembling, the shuttle is first bored and counterbored to provide the eye 3, key 110

seats 3¹, and passage 12. The bushing 6 is then inserted endwise through the outer end of the eye 3 with its key portions 9, 10 and 11 seated in the counter bores 3¹, 5 and if desired glued therein, after which the staple-like eye guard 13 is driven into the wood of the shuttle in such manner as to span the outer end of the bushing. If desired, the flat basal portion 6¹ of the 10 bushing may be notched as indicated at 6^a, Fig. V, and a screw 15 set through the wood of the shuttle from below may enter said notch to assist in retaining the bushing in place.

15 At its inner end, the bushing may be cut away as indicated at 6^b along that side adjacent the bobbin chamber of the shuttle, whereby to permit ready passage of the thread from the bobbin into the bore 7 of 20 the bushing after the shuttle has been threaded. The opposite wall at this end of the bushing serves as a snubbing post past which the thread from the bobbin runs in the threading operation and may be undercut 25 to provide an overhanging portion 6^c effective to prevent the thread from lifting upwardly as it is drawn through the threading slot 4.

30 Various modifications in the form and construction of my device may obviously be made, all without departing from the spirit of the invention, if within the limits of the appended claims.

35 What I therefore claim and desire to secure by Letters Patent is:

1. A thread conductor for the threading eye of a shuttle, consisting of a basal portion having ribs along its longitudinal edges effective to key the thread conductor in the 40 shuttle eye and a centrally disposed portion surmounting said basal portion and having a central cylindrical thread passage and a thread inlet slot opening into said thread passage.

45 2. A thread conductor for the threading eye of a shuttle, consisting of a basal portion having its longitudinal edges formed as ribs effective to key the thread conductor in the shuttle eye and a cylindrical portion 50 surmounting said basal portion and having an axial bore and a longitudinally extending thread inlet slot opening into said bore,

the inner end of said cylindrical portion on one side of said slot sloping downwardly to meet said basal portion. 55

3. A thread conductor for the threading eye of a shuttle, consisting of a basal portion having longitudinally extending ribs effective to key the thread conductor in the shuttle eye, and a tubular portion surmounting said basal portion and intersected along its upper edge and substantially continuously from end to end thereof by a thread inlet slot. 60

4. A thread conductor for the threading eye of a shuttle, consisting of a basal portion having ribs along its longitudinal edge effective to key the thread conductor in the shuttle eye, said basal portion having a marginal notch for the reception of a fastening, and a centrally disposed cylindrical portion surmounting said basal portion and having a thread inlet opening. 65

5. A thread conductor for the threading eye of a shuttle, consisting of a basal portion having oppositely disposed extensions effective to key the thread conductor in the shuttle eye, and a central portion surmounting said basal portion and disposed centrally between said extensions thereof and having an axial bore and a thread inlet slot opening into said bore, the inner end of said central portion at one side of said slot being undercut to provide a snubbing surface for the thread. 70 75 80

6. A thread conductor for the threading eye of a shuttle, consisting of a basal portion having longitudinally extending ribs effective to key the thread conductor in the shuttle eye, and a centrally disposed tubular portion surmounting said basal portion and providing a substantially cylindrical thread passage, said tubular portion intersected along its upper edge and substantially continuously from end to end thereof by a thread inlet slot opening into said thread passage. 90 95

In testimony whereof I affix my signature in presence of two witnesses.

JEAN B. DAUDELIN.
